VENTILATOR

Herman C. Hueglin, Chicago, Ill., assignor to
Federal Merchandise Company, Chicago, Ill.,
a corporation of Illinois

Application February 5, 1931. Serial No. 513,507

9 Claims. (Cl. 93—94)

This invention relates to ventilators.

It is old in the art to provide ventilating panels carrying an exhaust fan and adapted to be attached to the upper part of a window casement to permit the fan to exhaust the warm air, steam and odors of cooking from a kitchen. These prior art devices of which I am aware, are disadvantageous for the reason that their installation in the window casement interferes with the operation of the window sash, first in that the upper sash cannot be completely elevated to its normal position, and second that the lower sash cannot be fully opened when it is desired to do so.

My present invention has for its principal object the provision of a new and improved ventilator of this kind and an arrangement for supporting the same in a window casement, the arrangement permitting free and full use of both of the sashes of the window. The device built in accordance with the teachings of my present invention is simple and may be economically manufactured and installed, thereby rendering it additionally advantageous over the prior art devices.

The invention can be best understood by reference to the accompanying drawing in which:

Figure 1 is an elevational inside view of a window casement with the ventilating panel of my invention installed therein.

Figure 2 is a cross sectional view along the line 2—2 of Figure 1;

Figure 3 is a fragmentary cross sectional view taken along the line 3—3 of Figure 1; and

Figure 4 is a perspective view of the mounting bracket of my invention.

Referring now to the drawing in more detail, the ventilator of my invention consists of a metallic panel 1 having overturned edges into which retractable end pieces 3 and 4 are registered. The main panel 1 is provided in a standard length which fits into a majority of the windows, an accurate fit being accomplished through the extension of the members 3 and 4 into registration with the stops of the window casing. Centrally located in the main panel 1 is an opening opposite which the fan 5 is positioned, that fan preferably being a fan of the so-called exhaust type having a ring which is adapted to be attached to the panel member 1 in any convenient manner such as by bolts 7. Rising out of the ring 6 are arms 8 which extend toward the center of the frame and join with the motor casing 9 in which is located an electric motor by which the fan 5 is revolved. The particular details of construc-

tion of this fan unit are not of the essence of the present invention and may be varied within the teachings thereof.

Located near the upper edge of the main panel member 1 are slots 10 and 11 by which it is hung in the casement 12 of the window.

As will be best seen in Figure 2, the tongue 13 of the supporting hooks 14 are projected through these slots 10 and 11 to permit the panel to hang in the window opening.

These supporting brackets 14 are composed of a mounting plate 15 containing a plurality of countersunk holes 16 through which screws 17 are projected to attach the hooks to the stops 18 of the window casing.

Projecting out of the mounting plate 15 is a semi-circular projection 19 terminating in the tongue 13 upon which the panel hangs, this semi-circular portion 19 spacing the tongue away from the mounting plate 15 and holding it parallel to this plate.

In mounting the brackets 14 in the window casing, mounting plates 15 are placed on the stops 18 in such position that the outermost edge of the semi-circular projection 19 lies just inside of the track 20 in which the upper sash 21 of the window moves. The attachment of the hook to the window casement in this manner obviously permits free movement of the upper sash 21 throughout its entire path of travel, since the hooks are disposed completely on the inward or room side of this path.

The free end of the tongue 13 extends beyond the free end of the mounting plate 15 and is turned up slightly as shown at 22 to provide a hook-like end on the tongue, this end being useful in preventing the panel from sliding off of the hook as will presently appear.

After the hook has been placed upon the window casing in the foregoing manner and properly spaced thereon so that the tongues 13 will register with the slots 10 and 11 in the panel, the panel is installed in the window by simply hanging it upon these hooks. Because the motor housing 9 and brackets 8 of the fan mechanism project from one side of the panel 1, that panel, when free to swing, will hang at an angle with respect to a perpendicular, as is seen in Figure 2. Thus it will be seen that when the panel is pushed on the tongues 13 so that it abuts against the semi-circular closed ends 19 of the brackets, the lower end of the panel will, if free to do so, swing over into the path of the upper sash 21. Thus when the upper sash is lowered and the panel installed, the sash can be raised slightly

- to bring it into registration with the lower edge of the ventilating panel, thereby closing the opening at the top of the sash and permitting the upper edge of the upper sash 21 to aid in the support of the panel in the window opening. By extending the side members 3 and 4 into engagement with the side stops 22 of the window casing, the opening can be completely blocked and thereby made to present a neat and orderly appearance. The installation is completed by simply attaching the electric cord which is extended to the motor to a convenient outlet and the panel is thereby rendered ready for use.
- 15 During stormy weather and at other times when it is not desired to exhaust air from the room, the upper sash 21 can be raised fully by simply drawing the panel 1 back upon the tongues 13 of the brackets, to thereby bring the panel 20 out of the track of this sash. The sash is then raised and when the panel is released its lower edge rests against the side rails of the sash, because of the overbalancing of the panel by the motor assembly.
- 25 Of course when the panel is thus positioned in the top of the window, it is impossible to completely raise the lower, that is the inner sash of the window, and when it is desired to completely raise this sash, such as, for example, when the window is to be cleaned, the panel 1 is pulled inwardly of the window on the tongue 13 to bring it out of the path of the lower sash, thereby permitting that sash to be raised until its upper edge strikes against the tongue 13. Since the 30 tongue projects downwardly from the top of the window only a very short distance, the lock mechanism on the top of the sash will strike against the upper stop 18 at practically the same time that the top rail of the lower sash strikes the tongue 13, so the window can be raised as high as it could if the brackets 14 were not installed. Since the tongue 13 extends well inside of the path of the lower sash, the panel 45 can be moved sufficiently far to permit this sash to be fully operated without detaching it from the supporting brackets. The hook-like ends 22' of the tongues prevent the panel from accidentally sliding off the hooks during this operation.
- If for any reason it is desired to completely 50 remove the panel from the window, the electric cord is detached and the panel lifted off of the tongues 13 of the supporting brackets thereby freeing it and permitting its removal.
- From the foregoing it will be apparent that 55 I have provided a new and improved ventilating panel which can be economically manufactured since it is composed largely of sheet metal, and which panel can also be conveniently and at the same time securely installed in the window, this installation providing for the full operation of the window sash when necessary to do so, and also providing for the convenient removal of the panel from the window, if desired.
- 60 While I have chosen to show my invention by illustrating a preferred embodiment of it, I have done so by way of example only, as there are many modifications and adaptations which can be made by one skilled in the art, without departing from the teachings of the invention, and I am therefore not to be limited by the specific disclosure, but rather only by the scope of the appended claims.

What is claimed is:

- 75 1. The combination with a window having an inner and an outer sash mounted in a frame and

separated by stops, of a ventilator comprising a panel upon which a ventilating means is mounted, and a pair of U-shaped supporting hooks having one of their sides attached to the stops located

80 on opposite sides of the inner sash and at the top of the window frame, said stops being mounted with their closed ends outward, the free sides of said hooks projecting through slots in the panel to hang it in the window, said ventilating means overbalancing the panel to cause it to hang with its lower edge in the plane of the outer sash.

85 2. The combination with a window having an inner lower sash and an outer upper sash mounted in a frame and separated by frame stops, of a plurality of supporting hooks mounted on the stops adjacent the inner sash in such a manner as not to interfere with the outer sash, said hooks extending inwardly across the path of the lower sash and terminating adjacent the inside edge of the innermost ones of said stops, a ventilator panel having slots through which said hooks project to hang it in the window, and ventilating means mounted on one side of said panel, said means overbalancing the panel to cause it to turn 90 on said hooks and hang with its upper edge in the path of the lower sash and its lower edge in the path of the upper sash when said panel is in its normal position, and said hooks permitting the panel to be slipped out of the planes of the 95 sash when it is desired to raise both of them to the top of said window frame.

100 3. The combination of a metallic panel having over turned top and bottom sides and slots located adjacent its upper edge, retractable end pieces fitted into said overturned edges and projecting from said panel, mounting plates comprising a main portion adapted to be rigidly attached to a support and a tongue spaced from said main portion and located parallel to it, said 105 panel being hung by projecting said tongues through said slots and adjusted by sliding it longitudinally of said tongues to the desired position.

110 4. The combination of a rigid metallic panel, a ventilating means mounted thereon, extensible end pieces mounted on the panel and slidable with respect thereto to increase its effective length, and means for hanging said panel in a window, said means being disposed within and on the frame of the window and permitting the 115 upper sash of the window to be fully raised and permitting the panel to be swung about its upper edge as a pivotal axis to bring it into the path of that sash when the sash is lowered, said means including laterally extending portions providing 120 for movement of said panel and ventilating means out of the path of the lower sash of said window.

125 5. In combination with a rigid metallic panel having overbalancing ventilating means mounted thereon, a U-shaped hook member extending in a plane substantially normal to said panel for supporting said panel from the upper stop of a window frame, said panel being freely slidable laterally on said hook member to move it successively from the path of the upper window sash through the path of the lower window sash to a point outside of said paths to provide for raising both sashes to their upper limiting positions, and a turned up portion on said hook member preventing lateral sliding of said panel past said last named point.

130 6. In combination, in a window frame, a pair of spaced U-shaped supporting members secured to the upper sash stops of said frame and having 135

their open ends extending inwardly of said frame, 5
ventilating means including a metallic panel de-
pending from and pivoted about said members
within said frame, said panel being laterally slid-
able upon said members to position it with re-
spect to the window sashes in said frame, and
means on said hooks limiting lateral movement
of said panel.

7. In combination, in a window frame, a pair
10 of spaced U-shaped supporting members secured
across the upper sash stops of said frame and
extending across the stops of the lower window
sash to a point outside of said stops, ventilating
means including a metallic panel pivoted upon
15 and depending from said members and normally
maintained in over-balanced position to extend
angularly across the paths of the window sashes,
said panel being slidable laterally on said mem-
bers to position it out of the paths of said sashes
20 when moved in one direction, and to extend an-
gularly from said members into the path of the
upper window sash when moved in the opposite
direction.

8. A hook for supporting ventilating means in-
25 cluding a metallic panel within a window frame,

comprising an upper planar portion having open-
ings therein receiving means for securing said
hook to the upper sash stop of said frame, an in-
80 tegral tongue portion doubled back and extending
parallel to said upper portion of said hook in
spaced relation thereto, and an up turned tip
formed on the end of said tongue portion for lim-
iting sliding movement of said panel upon said
85 tongue portion.

9. In a window frame having stops defining the
paths of movement of upper and lower window
sashes, the combination of a pair of hook mem-
bers of substantial extent secured to said frame
90 and disposed normal to said stops, said members
extending across the stops for said lower win-
dow sash to a point outside of said paths of
movement of said sashes, ventilating means in-
cluding a metallic panel pivoted about and de-
pending from said hook members, and means for
95 limiting lateral sliding movement of said panel
on said hook members to dispose said panel in
the paths of said sashes in one position and out-
side of said paths in another position.
